UNITED STATES PATENT OFFICE.

WALLACE D. KIMBALL AND ARTHUR E. RIDEOUT, OF NEW YORK, N. Y., ASSIGNEES
TO STANDARD SEALING EQUIPMENT CORPORATION, OF NEW YORK, N. Y., A COR-
PORATION OF NEW YORK.

FILLED CARTON CLOSING AND SEALING MACHINE.

Application filed October 19, 1923. Serial No. 669,453.

The present invention relates to apparatus for silicating and closing the flaps of filled cartons.

In packing goods put up in individual packages, such as soap, canned goods, and the like, the cartons in which the commodity is shipped are commonly filled before the flaps at either the top or bottom are closed. The carton is filled and then set aside until such time as it may be sealed. In the sealing process silicate is manually applied to the carton flaps and a pressure subsequently exerted on the flaps by any suitable means for a period sufficiently long to insure a thorough setting of the cement.

It is a principal object of the present invention to provide apparatus of this type for automatically applying silicate to the flaps of filled cartons and closing the flaps, which apparatus employed in conjunction with the "sealing machine for filled cartons", constituting the subject matter of our co-pending application Serial No. 396,362, provides means for applying the silicate, closing the flaps, and holding them under pressure until the silicate has set, no further attention than merely placing the carton to be sealed on a receiving table at the entrance to the sealing machine being required.

A further object of the invention is to provide apparatus for silicating and closing the top and bottom flaps of filled cartons simultaneously, in a quick and convenient manner.

It is also an object of the invention to provide an apparatus of the above type in which the operating parts are of simple rugged construction and low cost, thus rendering the apparatus commercially practical.

It is a further object to provide in an apparatus of this character improved means for applying silicate to the flaps, which means operates in definite relation with the movement of the carton through the apparatus.

It is a still further object to provide an apparatus of this type constructed as a portable unit and conveniently adaptable to cartons of different dimensions.

We have illustrated a preferred embodiment of our invention in the accompanying drawings, in which Fig. 1 is a side elevation of a carton sealing machine in accordance with our invention; Fig. 2 is a transverse vertical section taken centrally of the ap-

paratus; Fig. 3 is a plan view of the apparatus; Fig. 4 is a perspective view illustrating the passage of cartons through the machine; and Fig. 5 is a detail view showing our improved silicate applying roller.

Referring to the drawings, the apparatus comprises a horizontal table 1 carried by a frame having legs 3 which serve to support the entire structure. These legs may conveniently be provided with rollers if desired, and when so equipped the entire apparatus is embodied in a portable unit which may easily be moved about for use in conjunction with other apparatus. The machine is here shown operating in conjunction with a pressure applying device 5 of the type disclosed in our co-pending application, Serial No. 396,362, the two machines being placed end to end and the cartons passing continuously through both and issuing therefrom ready for shipment. At the entrance end of the apparatus we preferably provide a roller table 4 upon which the filled cartons may be placed preparatory to sealing for facilitating their introduction into the machine. The carton supporting rollers and surfaces of the various parts of the apparatus are understood to be at the same height.

The carton supporting means comprises rollers 6 at one end of the apparatus for facilitating the introduction of the cartons, a second set of rollers 10 at the opposite end of the apparatus for facilitating the discharge of the sealed cartons, and specially shaped metal sheets 7, 8 and 9, shown more particularly in Fig. 2, positioned intermediate the two sets of rollers. The rollers may be supported by any suitable means, being here shown as mounted for rotation in the horizontal frame members 1. The specially shaped metal plates are preferably provided with brackets 11 for securing them to the frame of the machine.

The plate 7 is arranged at the same height as the upper edge of the rollers 6 and is placed immediately adjacent thereto. The edge adjacent the rollers is straight and is parallel to the axis of the rollers while the other end is cut away as shown at 12, forming a backwardly extending opening and leaving at the sides of the opening the two resilient prongs 13. Plate 9 is identical with plate 7 and symmetrically positioned, its edge which is adjacent the rollers 10 being

2
straight and parallel to the axis of the rollers. The width of the plates 7 and 9 is preferably about equal to that of the cartons being sealed. Plate 8 is centrally located and comprises a body portion somewhat wider than plates 7 and 9 at the center but which is cut away at each end to form the resilient tongues 14 extending centrally into the cutaway portions of the plates 7 and 9.

10 The filled carton is placed in the machine with the flaps which are to be sealed extending longitudinally of the machine. As the carton moves out upon the lower plate 15 7 the edges of the flaps pass out over the cutaway portion and, being unsupported, spring down due to the weight of the contents of the carton and also to the stiffness of the material composing the flaps. At the same time the weight of the carton and the contents presses down the resilient prongs 13 a slight amount and, as the forward movement of the carton continues the tongue 14 is inserted between the loose flaps 20 of the carton. The effect of the smooth curved edges on the plate 8 as the carton moves forward is to gradually unfold the flaps, and when the carton reaches the center of the plate the flaps have been unfolded 25 through approximately 180° and lie extending horizontally out at the sides of the carton, in which position they may be readily glued. As the carton moves on, the reverse of this unfolding process occurs. That is, 30 the flaps drop into an approximately vertical position as the carton moves out towards the end of the tongue 14, are engaged between the prongs of the plate 9 and are folded up, pressing the newly silicated portions against the inner flaps.

40 The silicate is applied to the flaps by rollers 15, one on each side of the carton, arranged to draw their supply of silicate from the tanks 16 and having their active surfaces 45 flush with the surfaces of the plates 8. The plates 8 are cut away beyond the rollers 15, best shown in Fig. 4, thus providing for the silicating of the entire width of the flap and preventing any contact with the silicated surfaces which would tend to remove 50 a portion of the silicate or smear it about. Rollers 17 are provided to cooperate with the rollers 15, the carton flaps being run between the two sets of rollers for securing 55 a uniform pressure during the application of the silicate.

A second series of plates 7, 8 and 9 are mounted in the upper part of the frame for sealing the top flaps, these plates being vertically adjustable to accommodate various sized cartons. The plate 8 serves to open the flaps and fold them out horizontally and the silicate is applied by means of rollers 15.

60 The silicating mechanism for the upper flaps 65 consists of a series of rollers arranged as

shown in the manner of ordinary inking rollers and deriving their supply from the tank 16 supported in the upper part of the frame out of the way of the passing carton. The rollers are preferably slidably mounted 70 in the frame or otherwise arranged for vertical adjustment to accommodate cartons of various heights. Thus the carton is moved continuously through the machine and the sealing operations are performed simultaneously upon the top and bottom flaps. 75

80 The means for conveying the carton through the machine comprises endless chains 24, one on each side of the machine, running over sprocket wheels 25 and interconnected at equally spaced intervals along their lengths by means of horizontal bars 26 set out some distance from the chains by means of arms 27. The chains may be driven by an electric motor or other convenient means, not shown. When the carton is placed on the rollers 6 it remains there until engaged by the rod 26, whereupon it is moved at a uniform rate through the machine. 85

90 Fig. 5 shows our improved silicate applying roller. The roller is provided with a cutaway portion in the direction of its length, as shown at 28. For a given length of carton flap a roller is employed whose circumference from one edge of the groove 28 around the roller to the other edge is just equal to the length of the flap. Thus, by starting the roller in the proper position relative to the carton, the flap is completely 95 glued after all of the outer periphery of the roller has contacted with it. This feature secures a quick cut off of the silicate supply and avoids smearing. The groove 100 also assists in lifting the silicate out of the tank. 105

110 In order that our improved silicating roller may be successfully applied it is necessary that the carton and roller move synchronously, and that the carton flap come directly opposite the roller at the same time at which the silicate applying surface of the roller has turned into contacting position. Furthermore, the time required for one revolution of the roller must be equal to the 115 time required by the conveying chains to travel a distance equal to that between successive horizontal bars 26. A synchronous relation is obtained by driving the silicate applying rollers by means of chains 29 and 30, respectively, connected to the same power source that supplies the sprocket wheels 25. Such a chain furnishes positive engagement, and once the proper setting of the rollers is obtained relative to the carton conveying chain no further attention is required. 120

125 From the above description the operation of the machine will be apparent. A carton is first filled, lifted upon the roller table 4, 130

and pushed into the machine during the interval elapsing between the passage of successive horizontal bars 26. It is to be noted that the roller table 31 is spaced away from the main body of the machine a sufficient distance to allow the rods 26 to pass freely. The carton rests upon the rollers 6 until it is engaged by one of the rods 26 and is then conveyed through the machine, its flaps being opened, silicated, and closed in successive operations as has been described. The successive operations are performed upon the top and bottom flaps simultaneously. At the end of the machine the carton is discharged into the pressure applying device 5, as shown.

Our improved carton sealing machine is preferably used in combination with a roller table for facilitating the introduction of the filled cartons and in conjunction with our pressure applying device, as is shown at 5, but may be employed alone or merely in combination with the roller table, which may or may not be built integrally with the sealing machine. Used individually as a unit it accomplishes the sealing and closing of the cartons, after which it is necessary to subject the discharged cartons to pressure for a length of time sufficient to allow the silicate to set.

The apparatus requires little floor space, since it is relatively long and narrow and may consequently be placed in otherwise unused space. This machine is particularly useful in factories where spare room is at a premium and cartage of the sealed cartons is undesirable. The entrance end of the apparatus may be placed at the point where the cartons are packed and the machine positioned to extend in the direction in which it is desired to move the sealed cartons, the discharge end being located at the point where the cartons are loaded for transportation.

In the appended claims, which define the scope of the invention, the word "silicate" is to be construed as meaning any preparation desired to be applied to flaps in the manner described, and the word "carton" is understood to designate any box, container, or the like, having flaps or edges to which a preparation is to be applied.

Various changes and modifications may be made within the full scope of the appended claims.

We claim:

1. A machine for sealing filled cartons comprising means for receiving a carton resting on its bottom flaps with its bottom flaps closed but unsealed, means for simultaneously opening the outside bottom flaps from closed position to a position to expose the inner surfaces of said flaps, means engaging the inner bottom flaps for supporting the carton during such operation, means

for gumming said surfaces, and means for thereafter closing said gummed flaps against the inner bottom flaps to thereby seal the bottom of the carton.

2. A machine for sealing filled cartons comprising means for receiving a carton resting on its bottom flaps with its bottom flaps closed but unsealed, means for simultaneously opening the outside bottom flaps from closed position to a position to expose the inner surfaces of said flaps, means engaging the inner bottom flaps for supporting the carton during such operation, means for gumming said surfaces, means for thereafter closing said gummed flaps against the inner bottom flaps to thereby seal the bottom of the carton, and means for simultaneously performing the same operations upon the outer top flaps.

3. A machine for sealing filled cartons comprising means for receiving a carton resting on its bottom flaps with its bottom flaps closed but unsealed, means for advancing the carton off of said carton-receiving means, a support in advance of said carton-receiving means and spaced therefrom by a distance less than the length of the carton, said support being adapted to engage the inner bottom flaps to support the carton and its contents and leave both outer bottom flaps free and having means for opening said flaps outwardly into substantially horizontal position, means for applying adhesive to said open flaps, and means for thereafter folding said flaps against the inner bottom flaps to thereby seal the bottom of the carton.

4. A machine for sealing filled cartons comprising means for receiving a carton resting on its bottom flaps with its bottom flaps closed but unsealed, means for advancing the carton off of said carton-receiving means, a support in advance of said carton-receiving means and spaced therefrom by a distance less than the length of the carton, said support being adapted to engage the inner bottom flaps to support the carton and its contents and leave the both outer bottom flaps free and having means for opening said flaps outwardly into substantially horizontal position, means for applying adhesive to said open flaps, means for thereafter folding said flaps against the inner bottom flaps to thereby seal the bottom of the carton, and means for sealing the top flaps of said carton.

5. A machine for sealing filled cartons comprising a support for a filled carton resting on its bottom flaps with its bottom flaps closed but unsealed, a tongue in advance of the said support but spaced away from said support to thereby leave a space between said tongue and said support extending the full width of said cartons, said tongue adapted to enter between the closed

outer flaps and the inner flaps of the carton before the carton is advanced off of said support to thereby support the carton and its contents while leaving both outer flaps free, means associated with said tongue for opening said outer flaps into a position to expose their inner surfaces, means for applying adhesive to said surfaces and thereafter closing said flaps against the inner bottom flaps to thereby seal the bottom of the carton.

6. A machine for sealing filled cartons comprising a support for a filled carton resting on its bottom flaps with its bottom flaps closed but unsealed, a tongue in advance of the said support but spaced away from said support to thereby leave a space between said tongue and said support extending the full width of said cartons, said tongue adapted to enter between the closed outer flaps and the inner flaps of the carton before the carton is advanced off of said support to thereby support the carton and its contents while leaving both outer flaps free, means associated with said tongue for opening said outer flaps into a position to expose their inner surfaces, means for applying adhesive to said surfaces and therefore closing said flaps against the inner bottom flaps to thereby seal the bottom of the carton, said last-named means comprising a second tongue projecting in the opposite direction from the first-mentioned tongue, and a third support for said carton spaced from said second-mentioned tongue, and having folders associated therewith to engage said outer bottom flaps and fold them against the inner bottom flaps as the carton passes from said tongue to said support.

7. A machine for sealing filled cartons comprising a support for a filled carton resting on its bottom flaps with its bottom flaps closed but unsealed, a tongue in advance of the said support but spaced away from said support to thereby leave a space between said tongue and said support extending the full width of said cartons, said tongue adapted to enter between the closed outer flaps and the inner flaps of the carton before the carton is advanced off of said support to thereby support the carton and its contents while leaving both outer flaps free, means associated with said tongue for opening said outer flaps into a position to expose their inner surfaces, means for applying adhesive to said surfaces and thereafter closing said flaps against the inner bottom flaps to thereby seal the bottom of the carton, said last-named means comprising a second tongue projecting in the opposite direction from the first-mentioned tongue, a third support for said carton spaced from said second-mentioned tongue, and comprising folders to engage said outer bottom flaps and fold them against the inner bottom flaps as

the carton passes from said tongue to said support, and means for simultaneously performing the corresponding operations on the top flaps of said carton.

8. A machine for sealing filled cartons comprising a machine bed, a carton support adjacent said machine bed but spaced therefrom, a conveyor for advancing the cartons through said machine, said conveyor comprising carton-engaging members contacting with said cartons above the plane of said machine bed, said carton-conveying members adapted to pass through the space between the said carton support and said machine bed, said machine bed being cut away throughout the entire width of said machine at a point in advance of the carton-receiving portion thereof, means in advance of said cut away portion for engaging the inner bottom flaps to support the carton and its contents and for simultaneously opening said outer bottom flaps from closed position and applying adhesive thereto, and means for closing said flaps against the inner bottom flaps comprising a carton-supporting member spaced from said inner flap-engaging support, said last-mentioned support having folders adapted to fold said flaps during the passage of the carton onto said last-mentioned support.

9. A machine for sealing filled cartons, comprising means for receiving a carton resting upon its closed unsealed bottom flaps, means for conveying cartons through the apparatus, a stationary plate above the carton and a similar plate below said carton for holding the carton flaps in closed position, said plates being recessed at their forward edges to relieve the forward edges of the carton flaps from closing pressure as said carton moves through the apparatus, a second set of plates positioned in advance of said first mentioned plates and having tongues adapted to engage the carton flaps and open them to a horizontal position, means for applying silicate to said flaps, and a third pair of plates adapted to engage the top and bottom flaps, respectively, and cause them to be closed.

10. In a machine for sealing filled cartons, three plates positioned in the same plane and distributed along the length of the apparatus, the two end plates being recessed at their inner ends and the third plate having a pair of tongues extending centrally into said respective recesses, whereby cartons entering the apparatus with bottom flaps folded but unsealed have said flaps opened and closed in combination with means for applying adhesive to said flaps while open.

11. In a machine for sealing filled cartons, three pairs of plates positioned in parallel planes for engaging the top and bottom flaps, respectively, of the carton, means for advancing cartons with the top and bottom

flaps closed but unsealed between said pairs of plates, the first pair of plates being recessed at their inner ends, the intermediate plates having tongues extending centrally 5 toward said recesses and similar tongues extending in the opposite direction, the third pair of plates having recesses facing said second-mentioned tongues whereby the top and bottom outer flaps of said cartons will be simultaneously opened and closed, and ¹⁰ means for applying adhesive to said flaps while in open position.

In testimony whereof we affix our signatures.

WALLACE D. KIMBALL.
ARTHUR E. RIDEOUT.

- flaps closed but unsealed between said pairs of plates, the first pair of plates being recessed at their inner ends, the intermediate plates having tongues extending centrally 10 toward said recesses and similar tongues extending in the opposite direction, the third pair of plates having recesses facing said second-mentioned tongues whereby the top and bottom outer flaps of said cartons will be simultaneously opened and closed, and means for applying adhesive to said flaps while in open position.
- 5 In testimony whereof we affix our signatures.
